JOHN A. KLINE AND CHARLES S. PRIZER, OF READING, PENNSYLVANIA,
ASSIGNORS TO THE READING STOVE WORKS, ORR, PAINTER & CO., OF
SAME PLACE.

DESIGN FOR A STOVE OR RANGE.

SPECIFICATION forming part of Design No. 27,628, dated September 7, 1897.

Application filed June 11, 1897. Serial No. 640,389. Term of patent 7 years.

To all whom it may concern:

Be it known that we, JOHN A. KLINE and CHARLES S. PRIZER, citizens of the United States, residing at Reading, county of Berks, 5 State of Pennsylvania, have invented a certain Design for Stoves or Ranges, of which the following is a specification.

The leading features of our design consist in the conformation of the stove and of the 10 parts forming the front portion thereof.

Figure 1 is a perspective view of our design of stove, and Fig. 2 shows separately the front panel-piece.

The oven-door 1, together with the ash-pit 15 and fire-box door 2, form jointly a single panel on the main body of the stove. Projecting beyond this main body and overhanging the base 34 of the stove is a bulging front inclosing about one-half the fire-box and having 20 ornamented ash-pit panels 5, which form forward extensions of the side plates 6 of the main body of the stove, a front ash-pit door 7 between said extended ash-pit panels, and a front panel-piece 8 above the door 7, hav-

ing its ends 13 curved rearward above the 25 ash-pit panels 5. The top plate 9 of the stove and the broiler-door 10 overhang the panel-piece 8, and the center of the fire-box lids 11 is about on line with the front end 12 of the main body of the stove. 30

What we claim is—

1. The design for a stove or range substantially as herein shown and described.
2. In a design for a stove or range the design for a side plate having a forwardly-extended ash-pit panel substantially as shown and described. 35
3. In a design for a stove or range the design for a front panel-piece substantially as shown and described. 40

In testimony whereof we affix our signatures in presence of two witnesses.

JOHN A. KLINE.
CHARLES S. PRIZER.
